UNITED STATES PATENT OFFICE

EDWARD BAUER, OF MILWAUKEE, WISCONSIN, ASSIGNOR, BY MESNE ASSIGNMENTS, TO BUCYRUS-ERIE COMPANY, OF MILWAUKEE, WISCONSIN, A CORPORATION OF DELAWARE

EXCAVATOR

Application filed March 24, 1926. Serial No. 97,009.

This invention relates to certain new and useful improvements in excavators and refers more particularly to a trip device for the dipper door.

While some types of excavators have been placed on the market as being capable of operation by one man, in actual practice it has been found necessary to provide an additional man to trip the dipper door, for due to a normal and necessary slack in the rope leading to the door trip, the operator must use both hands to quickly take up the slack and actuate the trip. As a result, the dipper oftentimes over-shoots the desired point of discharge and work is materially slowed.

Having the above and other objectionable features in mind, this invention contemplates as a primary object the provision of an improved mechanism whereby a minimum of effort is necessary to effect the tripping of the dipper door so that the services of but a single operator are required for the efficient operation of the excavator.

Another object of this invention resides in the provision of an improved device which may be readily applied to any type of excavator now in use or to excavators at the time of their construction and which prevents the occurrence of slack in the dipper door trip operating rope so that the door trip may be instantly operated, a prime mover being utilized to effect the operation of the trip.

A further object of this invention resides in the provision of an apparatus of the character described in which a motor is constantly rotated to maintain a tension on the dipper door trip cable and having means whereby an additional pull is applied to the cable by the motor to effect the tripping of the door.

And a still further object of this invention resides in the provision of an improved device of the character described having an actuating member located within convenient reach of the operator and requiring but an instant engagement to effect the tripping of the dipper door so that the operator need at no time relinquish control of the various levers for operating the excavator.

With the above and other objects in view which will appear as the description pro-

ceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated one complete example of the physical embodiment of my invention constructed according to the best modes I have so far devised for the practical application of the principles thereof, and in which:

Figure 1 is a side view of an excavator equipped with my invention;

Figure 2 is a view looking at the bottom of an excavator dipper illustrating one conventional type of dipper door lock;

Figure 3 is an enlarged view, partly in section and partly in elevation, illustrating the unit embodying my invention, and

Figure 4 is a view, partly in section and partly in elevation, illustrating a slightly modified type of unit embodying my invention.

The device constituting this invention is designed for operating the door of an excavator dipper whether it be steam, gasoline, electric or any other mechanically operated type and while the following description and accompanying drawings illustrate the application of the invention to a shovel of the electric type, it is to be understood that the use of the invention is not to be confined thereto.

Referring now more particularly to the accompanying drawings, in which like numerals designate like parts throughout the several views; the numeral 5 designates the turn table of an excavator on which an upper frame 6 is rotatably mounted, the frame 6 carrying the operating mechanism and having a boom 7 supported therefrom and braced by cables 8 connected with the upper end 9 of a truss frame 10 which braces the upper frame 6 against the torque of the boom. As is customary, the excavating dipper 11 is mounted on the outer end of a dipper handle 12 which is supported from the boom 7, as at 13, for movement longitudinally and

vertically about a horizontal pivot fixed with respect to the boom 7. As the specific shovel construction and operation forms no part of the present invention, further detail description thereof will be eliminated.

The dipper 11 has at its bottom closed by a door 14 which is hinged to the rear of the dipper, as at 15, so that the same normally tends to open when the dipper boom or handle is out of vertical position. Slidably mounted on the door in brackets 16 is a locking bolt 17, the outer end 18 of which is engageable in a keeper 19 fixed to the dipper proper and adapted to be received within an aperture 20 in the outer free edge of the door. The locking bolt 17 is yieldably urged to locking position by a contractile spring 21 having one end connected with the dipper door and its other end connected with a lever 22 which passes through a slot 23 in the rear end of the locking bolt and is pivoted, as at 24, to the door. A chain, cable or other operating member 25 has one end connected with the free end of the lever 22, as at 26, and its other end connected, as at 27, with a rotatable rod or drum 29 journaled, as at 30, in brackets carried by the dipper handle at a point adjacent its outer end, the drum 29 being rotatable to wind the member 25 thereon through the medium of a lever 31 having one end riveted or otherwise secured thereto, as at 32'.

The specific construction of the dipper door lock mechanism illustrated is of conventional design and the door 14 is closed by the manipulation of the dipper, as is customary in the operation of excavators, the bolt 17 swinging into the recess of the keeper 19 to lock the door closed. When it is desired to dump the dipper, the operator causes the lever 31 to be moved rearwardly through the medium of an actuating cable 32 which has one end connected with the free end of the lever, as at 33, so that the chain or other member 25 is wound about the drum 29 to disengage the bolt 17 from the keeper 19. As the tension on the cable 32 is released, the spring 21 unwinds the cable from the drum to permit the locking of the door after it closes.

As the dipper handle 12 is extended and retracted throughout substantially its entire length during the operation of the excavator, it is essential that sufficient slack be provided in the cable 32 to accommodate the maximum extension of the dipper and when the dipper is to be dumped when in retracted position, it is necessary that the slack in the cable be first taken up before movement can be imparted to the lever 31, as previously described. This results in considerable loss of time and in order to efficiently operate the excavator it is necessary to provide an additional operator whose duty it is to trip the dipper door, thus materially increasing the over-head ex-

pense incidental to the operation of the excavator.

Attempts have been made in the past to overcome these objectionable features such as exemplified in Letters Patent No. 1,435,709, issued David De Santo, November 7, 1922. As it is highly essential that the dipper door be tripped with a minimum of effort, if the excavator is to be entirely worked by a single operator, the device illustrated in the accompanying drawings provides a single control button, cord, or other actuating member which is located at a convenient place to the operator so designed that all that is required for the tripping of the door is but a momentary contact with the actuating member.

As illustrated, my invention is a unitary structure, consisting of a base 34 mounting a pair of up-rights or standards 35 having bearings 36 formed at their upper ends in which a drive shaft 37 is journaled. Mounted on the drive shaft between a friction plate 38 and a clutch plate 39 is a drum 40 provided with flanges 41 and 42 adapted to be frictionally engaged with the adjacent surfaces of the plates 38 and 39, respectively, which are lined with a friction lining of suitable material 43. The friction plate 38 is keyed or otherwise splined to the shaft 36, as at 44, and the clutch plate 39 is normally free thereon, being yieldably held free of the drum member by an expansile spring 45 mounted on the shaft 37 between the clutch plate and drum, said spring extending into a recess 46 in the adjacent end of the drum and pressing against one side of a bearing 47 for the drum.

Adjustable on the shaft 37 adjacent the clutch plate is a collar 48 which is provided with a plurality of radially extended pairs of ears or lugs 49 between which dogs or levers 50 are medially pivoted, the inner ends 51 of the levers being engageable with the outer inclined surface of the clutch plate and the outer ends 52 thereof being rounded and engageable with a cone collar 53 which is slideable on the drive shaft. The cone collar 53 has its outer portion annularly grooved, as at 54, to receive bearing blocks 55 pivotally connected, as at 56, with the ends of a yoke or U-shaped member 57 of an operating lever 58 which is medially pivoted, as at 59; from an extension 60 secured to the adjacent standard 35.

Fixed to the shaft 37 is a drive gear 61 with which a pinion 62 meshes, the pinion being carried by the shaft 63 of a motor or other prime mover 64 fixed to the base 34, as at 65. The base 34 is bolted or otherwise secured to the inclined member 66 of the truss structure 10. The inner end of the trip cable 32 is wound about the drum 40. The outer free end 67 of lever 58 has an operating or pull cord 68 fixed thereto which extends to a position located conveniently to the operator.

The prime mover 64 constantly operates when the excavator is in operation so that shaft 37 constantly rotates and the collar 48 is so adjusted on the shaft by means of a set screw 69 that the spring 45 exerts sufficient tension on the drum bearing 47 to urge the flange 41 of the drum into frictional engagement with the friction plate 38 so that the cable 32 tends to wind on the drum, to which result the friction between the plate 39 and the drum (through the spring 45) also contributes to some extent. The tension produced in the cable 32 by this total friction, however, is not enough to extend the spring 21 sufficiently to permit tripping the latch. The spring 45 in addition to maintaining this frictional contact, normally maintains the clutch plate free of the drum flange 42 and when it is desired to trip the dipper door, a slight pull is given the member 68 which moves the lever 58 on its pivot 59, forcing the cone 53 between the ends 52 of the levers 50 and moving the clutch plate 39 to engage its frictional surface 43 with the flange surface 42 to lock the drum to the shaft 37 and wind the cable 32 thereon. As the cable 32 winds on the drum, the lever 31 rotates drum 29 winding the cable or chain 25 thereon to disengage the locking bolt 17 from the dipper keeper 19.

As will be readily evident, when the parts are in the positions illustrated in Figure 3, there is a normal slip between the drum and the friction plates which is sufficient to maintain the cable 32 taut without overcoming the spring 21, but when the clutch plate 39 is moved to direct engagement with the drum, the drum is locked between the friction and clutch plates and turns with the shaft. There being no slack in the cable 32, the dipper door is instantly opened thus requiring but a momentary contact on the part of the operator's hand with the actuating member 68. After the operator has released the actuating member 68 the spring 45 instantly expands to disengage the clutch plate from the drum and the spring 21 being greater than the frictional contact between the drum and the friction plates unwinds the cable or chain 25 from the drum 29 returning the locking bolt 17 to its locked position.

In Figure 4, a slightly modified construction of my invention is illustrated wherein the lever 58 is operated by a solenoid 70 mounted on a bracket 71 secured to one of the standards 35 and having a tubular core 72 in which an armature 73 is slidable. The outer end of the armature is pivotally connected, as at 74, with the outer free end of the lever 58 and the mass of the armature is normally positioned below the magnetic center of the solenoid so that energization of the solenoid draws the armature into the core 72 raising the free end 67 of the lever and projecting the cone 53 between the ends 52 of the

levers 50, causing the drum 40 to rotate in the manner previously described.

The solenoid 70 is included in a circuit in which a source of energy 75 is connected which may be a battery or any other means and a switch 76 is located on one of the control handles 77 within convenient reach of the operator's hand. To dump the dipper, button 76 is pressed to complete the continuity of the solenoid circuit, energizing the solenoid and attracting the armature thereinto.

While I have illustrated an electrical motor as the means for actuating my improved device, it will be appreciated that any other appliance may be utilized such as a connection with the prime mover of the excavator proper, a turbine or any other means. The device being a unitary structure, as illustrated in Figure 3, may be readily applied to any style of excavator without requiring modification of its construction and thus may be sold as a unit entirely apart from the excavator.

What I claim as my invention is:

1. In an excavator having a dipper provided with a discharge door, a locking bolt for securing the door closed and a trip cable connected with the locking bolt whereby a pull on the cable greater than a certain amount permits the opening of the dipper door, a drive shaft, means for continuously rotating the drive shaft, a drum rotatably mounted on the drive shaft and about which the trip cable is adapted to be wound, a friction member fixed to the drive shaft, means providing a slipping frictional contact between the friction member and drum, whereby the drum normally tends to wind the trip cable thereon to maintain a tension on the cable sufficient to take up all slack therein but insufficient to actuate the locking bolt, and means for increasing the frictional contact between the friction member and the drum to increase the tension on the trip cable to a point sufficient to actuate the locking bolt.

2. In an excavator having a dipper provided with a discharge door, a locking bolt for securing the door closed and a trip cable connected with the locking bolt whereby a pull on the cable greater than a certain amount permits the opening of the dipper door, a drive shaft, means for continuously rotating the drive shaft, a drum rotatably mounted on the drive shaft and about which the trip cable is adapted to be wound, a friction member fixed to the drive shaft, means providing a slipping frictional contact between the friction member and the drum whereby the drum normally tends to wind the trip cable thereon to maintain a tension thereon sufficient to take up all slack therein but insufficient to actuate the locking bolt, and clutch means operable to drivingly connect the drum member with the shaft where-

by the cable is wound thereon and the locking bolt is withdrawn to release the dipper door.

3. In an excavator having a dipper provided with a discharge door, a locking bolt for securing the door closed and a trip cable connected with the locking bolt whereby a pull on the cable greater than a certain amount permits the opening of the dipper door, a drive shaft, means for continuously rotating the drive shaft, a drum rotatably mounted on the drive shaft and about which the trip cable is wound, a friction plate fixed to the drive shaft and engageable with one end of the drum, means providing a yielding engagement between the drum member and the friction plate whereby the drum tends to rotate with the shaft to maintain the trip cable taut without actuating the locking bolt, and a clutch plate engageable with the other end of the drum to increase the drive connection between the drum and shaft to an extent sufficient to withdraw the locking bolt.

4. In an excavator having a dipper provided with a discharge door, a spring pressed locking bolt for securing the door closed and a trip cable connected with the locking bolt whereby a pull on the cable greater than a certain amount permits the opening of the dipper door, a drive shaft, means for continuously rotating the drive shaft, a drum rotatably mounted on the drive shaft and about which the trip cable is wound, a plate fixed to the drive shaft and engageable with one end of the drum, means providing a slipping frictional engagement between the drum member and the friction plate whereby the drum tends to rotate with the shaft to maintain the trip cable taut without actuating the spring pressed locking bolt, a clutch plate engageable with the other end of the drum to increase the drive connection between the drum and shaft to an extent sufficient to withdraw the locking bolt, an actuating lever for the clutch, and an operating cable connected with one end of the lever and extended to a location convenient to the excavator operator whereby a slight pull thereon causes the clutch plate to increase the drive connection between the drum member and drive shaft.

5. In an excavator having a dipper provided with a discharge door, a locking bolt for securing the door closed and a trip cable connected with the locking bolt whereby a pull on the cable greater than a certain amount permits the opening of the dipper door, a drive shaft, means for continuously rotating the drive shaft, a drum rotatably mounted on the drive shaft and about which the cable is wound, a friction plate fixed to the drive shaft and engageable with one end of the drum, means providing a slipping frictional engagement between the drum member and the friction plate whereby the drum

tends to rotate with the shaft to maintain the trip cable taut without actuating the locking bolt, a clutch plate engageable with the other end of the drum to increase the drive connection between the drum and shaft to an extent sufficient to withdraw the locking bolt, an actuating lever for the clutch, a solenoid, an armature connected with the lever and arranged within the sphere of influence of the solenoid, an electric circuit including said solenoid, and a circuit making and breaking device for operating the circuit and located in a position convenient to the excavator operator.

6. In an excavator having a dipper provided with a discharge door, a locking bolt for securing the door closed and a trip cable connected with the locking bolt whereby a pull on the cable greater than a certain amount permits the opening of the dipper door, a drive shaft, means for continuously rotating the drive shaft, a drum rotatably mounted on the drive shaft and about which the trip cable is wound, a friction plate fixed to the drive shaft and engageable with one end of the drum, means providing a yielding engagement between the drum member and the friction plate whereby the drum tends to rotate with the shaft to maintain the trip cable taut without actuating the locking bolt, and a clutch plate engageable with the other end of the drum to increase the drive connection between the drum and shaft to an extent sufficient to withdraw the locking bolt, the means last above mentioned serving normally to hold the clutch plate out of the operative engagement with the drum.

7. In an excavator having a dipper provided with a discharge door, a locking bolt for securing the door closed and a trip cable connected with the locking bolt whereby a pull on the cable greater than a certain amount permits the opening of the dipper door, a drive shaft, means for continuously rotating the drive shaft, a drum rotatably mounted on the drive shaft and about which the trip cable is wound, a friction plate fixed to the drive shaft and engageable with one end of the drum, spring means providing a yielding engagement between the drum member and the friction plate whereby the drum tends to rotate with the shaft to maintain the trip cable taut without actuating the locking bolt, and a clutch plate engageable with the other end of the drum to increase the drive connection between the drum and shaft to an extent sufficient to withdraw the locking bolt, the spring means serving normally to hold the clutch plate out of operative engagement with the drum.

8. In a trip for power shovels, the combination of: a trip cable; two constantly rotating power disks; a drum for said trip cable located between said two disks; single means normally tending to hold one of said

disks in frictional contact with the drum and the other disengaged therefrom; and means for clamping the drum between the two disks.

5 9. In a trip for power shovels, the combination of: a trip cable; two constantly rotating power disks; a drum for said trip cable; single means normally tending to hold one of said disks in frictional contact with the drum and the other disengaged therefrom; and means for engaging the drum and the normally disengaged disk.

10 10. In a trip for power shovels, the combination of: a trip cable; two constantly rotating power disks; a drum for said trip cable; single means normally tending to hold one of said disks in frictional contact with the drum and the other disengaged therefrom; and means for engaging the drum and the normally disengaged disk, and at the same time increasing the pressure between the drum and the normally contacting disk.

15 11. In a semi-automatic trip for power shovels, a trip cable, a drum therefor, power means, manually actuated means for connecting the power means with the drum, a friction member normally pressing against the drum, said friction member being connected with the power means so as to be rotated thereby, a spring for causing said friction member 20 to engage the drum continually, means for adjusting the tension of said spring whereby a proper friction may be secured for causing the drum to take up any slack in said cable without however imparting sufficient 25 tension to said cable to cause it to function for tripping purposes.

30 12. In a power dipper door latch releasing device, a rotatably mounted shaft, a pair of friction disks carried by said shaft, one of 35 which disks is movable toward and away from the other, a drum mounted for independent rotary movement between said disks, a cable secured to and adapted to wind upon 40 said frame, which cable is connected to the dipper door latch of the shovel with which 45 the device is associated, manually operable means for causing the disks to frictionally engage the cable carrying drum with sufficient force to actuate the cable for tripping, 50 and yielding pressure means associated with said manually operable means for producing sufficient frictional connection between the shaft and the drum to cause said drum to rotate and take up the slack in the cable that is 55 carried thereby.

In testimony whereof I affix my signature.
EDWARD BAUER.
